A. SALIGER

RAMMER

Filed July 5, 1921

Inventor:
Aston Saliger,
by Comst Co.,
his attorneys.

UNITED STATES PATENT OFFICE.

ANTON SALIGER, OF ST. LOUIS, MISSOURI.

RAMMER.

Application filed July 5, 1921. Serial No. 482,302.

To all whom it may concern:

Be it known that I, ANTON SALIGER, a citizen of the United States, and a resident of the city of St. Louis and State of Missouri, have invented a new and useful Improvement in Rammers, of which the following is a specification.

This invention relates principally to fluid operated rammers of the kind used by metal founders for ramming, compressing or packing molding sand about the molding pattern, whereby the sand is made to conform accurately to the surfaces of the pattern, and it relates particularly to the rammer-15 head or butt for said rammers.

One of the principal objects of the present invention is to provide the rammer-butt with an elastic pad for the protection of the butt and pattern during the packing-20 of the sand. Another object is to removably secure the pad to the butt, whereby the pad is adapted to be replaced when it becomes worn or damaged. Another object is to eliminate the need for separate-25 fastening members, such as screws and bolts, for securing the pad to the butt, which fasteners are liable to become loosened during the ramming operation and damage the pattern. Other objects are to simplify the-30 construction and to reduce the cost of manufacture.

The invention consists principally in a rammer-head or butt adapted to be attached to the piston of a rammer and a tip or pad-35 of india-rubber or other suitable elastic substance adapted to be detachably secured to said butt; and it also consists in the combinations and arrangements of parts hereinafter described and claimed.

40 In the accompanying drawing, which forms part of this specification, and wherein like symbols refer to like parts wherever they occur,

Fig. 1 is a side elevation of the forward-45 end of a portable sand-rammer provided with a butt embodying my invention;

Fig. 2 is a central longitudinal section through said butt, the forward end portion of the piston being shown in elevation;

50 Fig. 3 is a central longitudinal section through the metallic body portion of said butt; and

Fig. 4 is a perspective view of the impact-piece therefor.

55 Referring to the accompanying drawing, my invention is shown in connection with

an ordinary portable fluid-operated sand-rammer comprising a cylinder 5 and a piston 6 working therein. The piston 6 is reciprocated longitudinally of the cylinder 5 by means of fluid pressure which is controlled by the usual valves (not shown) at the handle-end of the rammer. The piston extends through suitable packing (not shown) at the outer end of the cylinder 5, which packing is held therein by means of a packing-nut 7 provided with a lock-nut 8.

The piston projects forwardly beyond the packing-nut 7 and has a tapered end portion 9 adapted to receive a metallic rammer-head or butt comprising a metallic body portion 10 and a detachable impact-piece preferably in the form of an elastic pad 11. The rammer-head 10 is preferably made of aluminum and comprises a cylindrical base portion and a substantially conical upper portion.

The rammer-head has a cylindrical steel sleeve or bushing 12 cast therein concentric with the longitudinal axis thereof. The upper end of the bushing 12 terminates flush with the top surface of the rammer-head. The lower end of the bushing is closed by the metal of the rammer-head. The bore 13 of the bushing 12 is tapered to fit the tapered end portion 9 of the piston 6; and said bushing is provided midway between its ends with a circular flange or collar 14, which prevents endwise movement of said bushing with respect to said rammer-head.

The base of the rammer-head is provided with an undercut circular cavity or recess 15, adapted to receive a similarly undercut circular head portion 16, formed on the upper end of the elastic pad 11, the recess 15 and the head 16 being substantially of a corresponding size and shape. This arrangement constitutes in effect a dove-tail joint between the rammer-head and the impact pad and firmly secures the pad to the rammer-head without the use of separate fasteners. The pad 11 is attached to the rammer-head 10 by forcing the undercut head portion 16 of said pad into the undercut recess 15 of said rammer-head, the elasticity of the pad permitting the undercut head portion to contract sufficiently to permit the larger diameter of the head to clear the smaller diameter of the undercut recess. The impact pad protects the rammer-head and pattern and can be readily attached to

said head and detached therefrom. The elasticity of said pad causes the rammer to strike a yielding blow, thus causing the sand to conform more accurately to the pattern. The elastic pad is preferably made of india-rubber or other suitable elastic substance.

It is noted that the use of the hardened steel bushing 12 prevents enlargement of the piston receiving hole 13 of the rammer-head and permits the body of the rammer-head to be made of aluminum or other soft lightweight metal.

Obviously the construction hereinbefore described admits of considerable modification without departing from my invention. For instance, the base of the rammer-head may be provided with an undercut channel, and a non-elastic pad may be provided with a similarly shaped undercut rib adapted to fit in said channel, the dove-tail joint thus formed preventing the separation of the pad from the rammer-head except by force applied in the direction of the length of said channel and said rib.

What I claim is:

1. A rammer-head comprising a body member and an impact piece therefor, said body member and said impact piece being formed with mating undercut portions, whereby they are detachably secured together.

2. A rammer-head comprising a body member and an elastic pad therefor, said body member and said elastic pad being formed with mating undercut portions, whereby they are detachably secured together.

3. A rammer-head comprising a body member having an undercut recess in the base thereof, and an elastic pad having an undercut head portion adapted to fit the undercut recess in said body member.

4. A rammer-head comprising a body member having an undercut circular recess in the base thereof, and an elastic pad

having an undercut head portion adapted to fit said circular recess.

5. A rammer-head comprising a body member having a hardened steel bushing 50 therein whose bore is tapered to fit the tapered end of a piston of a rammer, said body member having an undercut circular recess formed in its base portion, and an elastic pad having an undercut circular 55 head portion adapted to be forced into said undercut recess, whereby said pad is detachably secured to said rammer-head.

6. A rammer head comprising a body portion having an undercut circular recess 60 formed in the base thereof, and an elastic pad having an undercut circular head portion of a size and shape corresponding substantially to the size and shape of said recess, the head portion of said elastic pad being adapted to be forced into said recess in said rammer-head, whereby said pad is detachably secured to said rammer-head.

7. A rammer head comprising a body portion having a hardened steel bushing 70 therein, said bushing having a tapered bore adapted to receive the tapered end of a piston of a rammer.

8. A rammer-head comprising a body member having a bore which is tapered to 75 fit the tapered end of a piston of a rammer, said body member having an undercut circular recess formed in its base portion, and an elastic pad having an undercut circular head portion adapted to be forced into said 80 undercut recesses, whereby said pad is detachably secured to said rammer-head.

9. A resilient tamping butt for rammers, comprising a shank having a mortise in its lower side, and a rubber butt having a 85 tenon on its upper side adapted to engage the mortise of the shank, and means for frictionally connecting the shank to the end of the rammer rod.

Signed at St. Louis, Missouri, this 1st 90 day of July, 1921.

ANTON SALIGER.
